UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

TELEPHONE RECEIVER.

Application filed August 22, 1924. Serial No. 733,477.

This invention relates to a telephone receiver which may be adapted for a number of uses, such as a head phone or as a loud speaker used in radio circuits.

5 It is the object of my invention to provide a construction in which the interior parts of the receiver are very much simplified, at the same time increasing the general effectiveness of the receiver.

10 Other objects will be apparent from a reading of the specification taken in connection with the annexed drawing, wherein:

Figure 1 is a plan view of the receiver 15 with the ear cap removed.

Figure 2 is a sectional view along the lines 2-2 of Fig. 1, while

20 Figure 3 is a bottom view of the interior parts of the receiver as withdrawn from the shell.

In the drawings, 1, is a shell threaded to receive the usual ear piece which is used for clamping a diaphragm, neither of these parts being illustrated.

25 A novel feature of my construction is in the magnet pole pieces which are best illustrated in Fig. 3; these are preferably made from stamped sheet steel of the proper character or of soft Norway iron. Pole pieces 3 and 4 have projecting arms 5 and 6 respectively. The arms 5 and 6 are of substantially the same width and contour as the permanent magnet which rests in the shell 1 directly over said arms and pole 30 pieces.

35 The pole pieces have upwardly turned arms 7 on which electro-magnetic windings 8 are positioned; ears 9 are also formed on each of the pole pieces 3 and 4 which extend outwardly in the same plane as the flat surfaces of the pole pieces. These ears act as supporters for the spool heads 10. In assembling the receiver, the windings 8 are placed on the projecting end 7 of the pole 40 pieces 3 and 4 which are then placed in the bottom of the shell. The magnet 11 is then put in place and on top of the magnet looking at Fig. 1 is placed an insulator 13 and then a second insulator 12 following which

45 the screws 14 are passed through the shell 1, the pole pieces 3 and 4, and the insulators 12 and 13 and nuts 15 applied. On the insulator 13 is mounted terminal clips 16 and 17 which have ears 19 that pass through 50 the insulator 12 and are clenched over on

the bottom side thereto. It will thus be seen that the insulator 12 is used to prevent these bent over portions of the terminals 16 and 17 from coming in contact with the magnet 11. The ends of the windings 8 are connected to the terminal clips 16 and 17 which are also provided with holes 20 and 21 through which cord terminals pass and which are clamped in said holes by the bent over portion 22 of the terminal clips. The 60 cord terminals pass through the openings 23 in the shell 1, and from the position of the terminals 16 and 17 it will be seen that the cord terminals are completely enclosed within the receiver shell. As one means for 65 taking the strain away from the cord terminals, I may use a clip 24 having an arm passing over one of the screws 14, the body portion of the clip lies along the inner surfaces of the shell 1 and has notches fitting 70 over the cords as they come through the openings 23 in the shell.

75 From what has been said it will be observed that the arms 5 and 6 have pole pieces 3 and 4 engaged in the inner wall of the shell 1, and thereby act to hold the vertical end 7 in substantially parallel relationship; at the same time, the pole pieces are in large area contact with the magnet which I have found 80 to be advantageous.

85 It will be readily observed that my invention is susceptible to numerous changes in details and I therefore do not wish to be limited as by the scope of the appended 90 claims.

Having thus described my invention, what I claim is:

1. In a device of the class described including a casing, pole pieces having arms following the contour of the casing, a permanent 95 magnet lying over said pole pieces and arms, a circular shaped insulator lying on said magnet on the side toward the edge of the casing, a second insulator on the first insulator carrying cord and winding terminals and means for fastening said insulators, magnet, and pole pieces to said casing.

2. In a device of the class described, including a casing, pole pieces within the casing and having free ends with windings thereon, a permanent magnet lying over said pole pieces, a circular shaped insulator positioned on said magnet on the side toward the free ends of said pole pieces, a second in- 100 105 110

sulator positioned on said first insulator, said second insulator carrying cord and winding terminals and means for fastening said insulators, magnet, and pole pieces to said casing.

3. In a device of the class described including a casing, a magnet, windings having core projecting ends overlapping said magnet throughout the major portion of its 10 arcuate length, said cores having free ends terminating slightly below a plane taken across the top of the casing, and an insulator carrying combined cord and winding terminals positioned on the side said magnet 15 toward said core free ends, and means for preventing said terminals from contacting with the magnet.

4. In a device of the class described including a casing, a magnet, windings having

core projecting ends overlapping said magnet, an insulator carrying combined cord and winding terminals, said casing having openings therein through which cord terminals may be passed and a retaining clip fastened within the casing for engaging said cord strands for removing the strain from said last mentioned terminals.

5. In a device of the class described including a casing, a magnet, pole pieces having projecting arms of substantially the same 30 width as the magnet and lying on the bottom of the casing below said magnet, a pair of insulators positioned on the top of said magnet toward the open end of the casing, and cord and winding terminals fastened to the 35 outer of said insulators.

In testimony whereof, I affix my signature.
EDWARD B. NOWOSIELSKI.
